US00D838991S

(12) **United States Design Patent** (10) **Patent No.:** **US D838,991 S**
Choi et al. (45) **Date of Patent:** **** Jan. 29, 2019**

(54) **TOOTH BRUSH HANDLE WITH BRUSH HEAD**

(71) Applicant: **KONINKLIJKE PHILIPS N.V.**,
Eindhoven (NL)

(72) Inventors: **Shaun Seongwon Choi**, Hong Kong (HK); **Chun Pong Yuan**, Hong Kong (HK); **Bart Johannes Massee**, Haarlem (NL)

(73) Assignee: **KONINKLIJKE PHILIPS N.V.**,
Eindhoven (NL)

(**) Term: **15 Years**

(21) Appl. No.: **29/653,804**

(22) Filed: **Jun. 19, 2018**

(30) **Foreign Application Priority Data**

Dec. 20, 2017 (EM) 004557536-0001

(51) **LOC (11) Cl.** **04-02**

(52) **U.S. Cl.**
USPC **D4/101**

(57) **CLAIM**

The ornamental design for a tooth brush handle with brush head, as shown.

DESCRIPTION

FIG. 1 is a perspective view showing my design;
FIG. 2 is a front elevational view thereof;
FIG. 3 is a rear elevational view thereof;
FIG. 4 is a right side elevational view thereof;
FIG. 5 is a left side elevational view thereof;

(Continued)

FIG. 6 is a top plan view thereof; and,
 FIG. 7 is a bottom plan view thereof.
 The broken lines shown in the figures depict portions of the
 article that form no part of the claimed design.

1 Claim, 2 Drawing Sheets
